CLAIM

The ornamental design for a non-electric household hand held cutting device, as shown and described.

DESCRIPTION

FIG. 1 is a front view of the device;

FIG. 2 is a back view of the device;

FIG. 3 is a top perspective view of the device;

FIG. 4 is a side view of the device;

FIG. 5 is a back view of the device;

FIG. 6 is a side view of the device;

FIG. 7 is an end view of the device showing details; and,

FIG. 8 is an end view of the device.
